DESIGN FOR A JAR WRENCH

Benjamin F. Hayden, St. Louis, Mo.

Application April 19, 1944, Serial No. 113,302

Term of patent 7 years

(Cl. D44—29)

To all whom it may concern:

Be it known that I, Benjamin F. Hayden, a citizen of the United States, residing in the city of St. Louis, in the State of Missouri, have invented a new, original, and ornamental Design for a Jar Wrench, of which the following is a specification, reference being had to the accompanying drawing, forming a part thereof.

Figure 1 is a top plan view of a jar wrench, showing my new design, with the handles thereof closed together.

Figure 2 is a view similar to that of Figure 1, with the handles thereof opened apart.

Figure 3 is a bottom plan view, showing the handles opened apart.

Figure 4 is an edge view, looking towards the left of Figure 1.

I claim:

The ornamental design for a jar wrench, as shown.

BENJAMIN F. HAYDEN.
